VEHICLE SIGNAL

Filed Aug. 15, 1922

Patented Feb. 10, 1925.

1,526,135

UNITED STATES PATENT OFFICE.

GUY F. GILSON, OF LOS ANGELES, CALIFORNIA.

VEHICLE SIGNAL.

Application filed August 15, 1922. Serial No. 581,924.

To all whom it may concern:

Be it known that I, GUY F. GILSON, a citizen of the United States, residing at Los Angeles, county of Los Angeles, State of California, have invented new and useful Improvements in Vehicle Signals, of which the following is a specification.

This invention is a signaling device particularly adapted for use upon motor vehicles to signal other vehicles of an intended turning or stopping of the machine.

It is the object of the invention to provide a simple and compact signal structure which may be readily mounted in position, and which may be as conveniently taken apart.

More specifically, it is the object of the invention to provide a casing forming a central compartment and projecting signal compartments, with electric lamps for the signal compartments in the central chamber, and a detachable supporting backing for the casing carrying partitions arranged to extend into the central compartment and separate the signal chambers, said casing and backing having electrical contacts arranged for abutting engagement when the parts are assembled, so as to provide electrical connections for the signal lamps.

The invention will be readily understood from the following description of the accompanying drawings, in which:

Fig. 1 is a rear elevation of the signaling device, partly broken away.

Figs. 2 and 3 are detail sections on the lines 2—2 and 3—3 of Fig. 1.

Fig. 4 is a rear elevation of the supporting backing for the device.

Fig. 5 is a detail section of the insulator sheet and one of the contacts carried thereby.

The casing for the signal comprises a central chamber 1 having an open back, and radially projecting signal compartments 2, which are preferably elongated rectangular structures open at their inner ends to chamber 1.

In the present instance, three of the signal compartments are shown, one of said compartments preferably extending horizontally from the central chamber, with the other two compartments projecting vertically upwardly and downwardly from said central chamber. In this construction, the upwardly extending compartment is employed for signaling a turn to the right, the horizontally projecting compartment is used

to denote a turn to the left, and the downwardly extending compartment carries a stop signal.

The indicating means for the various signals may consist of the words "Right," "Left," and "Stop" stenciled in the walls of compartments 2. In practice, the words are cut in the front walls of the signal compartments as shown at 3, and the initial letters of the words are cut in the rear walls of the compartments as shown at 4.

Transparent plates 5, preferably of red glass, are mounted in guides 6 within the respective signal compartments, so as to extend over the openings 3 and 4, and partitions 7 are arranged within the compartments between openings 3 and 4, so as to prevent blurring of the signals by light shining through aligned openings 3—4.

The illuminating means for the signal compartments are mounted within the central chamber 1. As an instance of this arrangement an insulator block 10 is positioned at the front wall of chamber 1, and spring contact strips 11, one for each of the compartments 2, are mounted on said block. Lamp sockets 12 are arranged in front of each of the strips 11, and in alignment with the signal compartments, and usual electric lamps 13 are removably secured in said sockets so as to make electrical contact with the strips 11.

Strips 11 are in turn electrically connected to yieldable contact elements 14, as by the wires 15; said contact elements being yieldably urged outwardly by springs 16 received in insulator casings 17. Cups 20 carried by the wall of chamber 1, support the yieldable contact members adjacent the respective lamps, and with the ends of said members extending outwardly through the open back of chamber 1.

A closure plate is provided for the open back of the central compartment of the lamp casing. This closure plate or backing is shown at 21, and has a conduit 22 extending from the outer face thereof and opening through said plate. The conduit forms attaching means for supporting the signaling device, and is also adapted to receive electrical wires for the lamps 13.

Partitions are mounted on the inner face of plate 21, and are arranged to project into chamber 1 when the lamp casing and the backing plate are assembled. As an instance of this arrangement, the partitions 23 are

provided at one edge with angularly disposed lips 24 which are adapted to rest upon plate 21, and thereby support the partitions in position projecting from said plate.

- 5 A sheet 25 of insulating material, is fixed against the inner face of plate 21, so as to overlie the lips 24 and thereby hold the partitions in place, it being understood that said sheet is suitably slotted to permit the 10 partitions to project through the same.

With the construction set forth, three of the partitions are employed, they being angularly disposed relative to one another, so as to form spaces between adjacent partitions which will receive the respective lamps 13 and their electrical connections, when the partitions are placed in position within chamber 1.

When the open back of chamber 1 is 20 closed by plate 21, so as to bring the partitions into operative position as just set forth, it will be seen that the respective signaling compartments and the lamps for the same will be separated by said partitions, 25 and the latter will form closure means for the inner ends of the respective signal compartments, so that when one of the lamps 13 is illuminated, the light therefrom will only shine into the aligned compartment 2.

- 30 Electric contacts 26 are mounted upon the insulator sheet 25, as for example, by means of studs 26^a integral with said contacts and threaded into said sheet, the said contacts being positioned for abutment against contacts 14 when the backing plate 21 is secured to the lamp casing; and wires 27 are welded or otherwise suitably connected to contacts 26, and extend through the conduit 22 to a suitable source of electrical energy. 35 A grounded wire 28 may also extend through the conduit and be connected to the plate 21, in order to complete the electrical circuit.

When the parts are assembled as thus described, the backing plate 21 may be connected to the lamp casing, by bolts 30 mounted in the central chamber 1 and adapted to project through holes 31 in the backing plate, said bolts having nuts 32 received thereon.

The structure as thus set forth provides a convenient signaling means, since the lamp casing and the lamps may be readily removed when necessary, without disturbing the backing plate and its supporting means. 55 When the parts are assembled, any desired signal lamp may be illuminated, by closing

a suitable switch in the electrical circuit for the lamp, and the desired signal compartment will thus be illuminated while the 60 other compartments remain dark. As a consequence, a positive and efficient signaling means is provided.

While I have illustrated and described but one practical embodiment of the device, 65 it will be apparent that various changes may be made in the construction, combination, and arrangement of parts, without departing from the spirit of the invention.

What is claimed is:

1. Signaling means comprising a lamp casing having an open back, a backing for said casing, partitions for said casing having angularly disposed edges received against said backing, and a sheet having 75 openings with said partitions projecting therethrough, said sheet being supported upon said backing and overlying said angular edges of the partitions to mount the latter on said backing.

2. Signaling means comprising a lamp casing having an open back, a backing for said casing, partitions for said casing having angularly disposed edges received against said backing, an insulator sheet having openings with said partitions projecting therethrough, said sheet being supported upon said backing and overlying said angular edges of the partitions to mount the latter on said backing, electrical contacts carried by said insulator sheet, and electrical conductors connected to said contacts and extending outwardly through said backing.

3. Signaling means comprising a casing forming a central compartment having an open back, and radially extending signal compartments, a backing for said central compartment, partitions carried by said backing and adapted to close the inner ends of the respective signal compartments, 100 lamps in said central compartment within the respective spaces formed by said partitions, yieldable electrical contacts in said central compartment normally urged toward said open back, electrical connections 105 between said contacts and said lamps, and fixed electrical contacts carried by said insulator means, said contacts being adapted to be engaged by said yieldable electrical contacts when said casing is mounted on said 110 backing.

In testimony whereof I have signed my name to this specification.

GUY F. GILSON.
